UNITED STATES PATENT OFFICE.

HERMANN A. KLEMM, OF NEW YORK, N. Y.

LOOP-SPREADER MECHANISM FOR SEWING-MACHINES.

SPECIFICATION forming part of Letters Patent No. 726,310, dated April 28, 1903.

Application filed February 28, 1901. Serial No. 49,189. (No model.)

To all whom it may concern:

Be it known that I, HERMANN A. KLEMM, a citizen of the United States of America, and a resident of New York city, county and State 5 of New York, have invented certain new and useful Improvements in Loop-Spreaders Mechanism for Sewing-Machines, of which the following is a specification.

My invention consists of improvements in 10 hook-thread-loop spreading apparatus for glove-sewing machines in which the looping-hook has lateral movement across the path of the needle for opening the hook-thread loop, which is a kind of machine that is especially desirable to use for sewing gloves owing to its 15 light and simple construction and its special adaptation for high speed, and the invention is especially adapted for overcoming a constant tendency to skip stitches, particularly when 20 in turning the work quickly in sewing around the finger-tips the hook-thread is apt to be drawn around in the throat out of the feed-line and relatively to the needle, so that the needle fails sometimes to catch the loop-thread. The essential feature of my invention 25 is, however, a more simple and cheaper contrivance of the spreader apparatus, as hereinafter described, reference being made to the accompanying drawings, in which—

30 Figure 1 is a side elevation of the looping-hook and its operating mechanism, also the loop-spreading apparatus, the work-plate presser-foot, and part of the needle. Fig. 2 is a plan view of the apparatus represented 35 in Fig. 1. Fig. 3 is a perspective view of parts, showing the point of the hook entering the needle-thread loop and the position of the loop-spreader at the same time. Fig. 4 is a similar view showing further advance of the looping-hook and spreader. Fig. 5 is another similar 40 view showing still further advance of the hook and the spreader. Fig. 6 is another similar view showing the retiring hook with its loop engaged by the loop-spreader, and Fig. 7 is another similar view with the hook-spreader and needle in the positions they take after 45 completing a stitch and preparatory to the beginning of another stitch.

The machine is of the kind in which the hook 50 first passes the needle at one side for engaging the needle-thread loop and then shifts laterally under the needle for spreading the

loop, so that in the beginning of its next movement the needle passes down at the other side of the hook through the hook-thread 55 loop for engaging it by the needle-thread, through the loop of which the hook passes on the next forward movement, the spreader being employed for opening the hook-thread loop reversely to the opening by the hook for 60 such passage of the needle through it.

The hook and its operating mechanism are of common construction, but are represented in the drawings and described for better understanding of the construction and operation 65 of the spreader, which is the subject of the claim.

The needle-operating mechanism and feed mechanism will be of common construction, which need not be shown or described further than to indicate the needle A.

The hook *a* is carried on a rocking pivot *b*, which is mounted in the yoke-head *c* of a rock-shaft *d*, to which rocking motion is communicated from a cam (not shown) on the main 75 shaft *e*, through the arm *f*, as in other machines of like construction.

The pivot *b* of the hook *a* is coupled by the arm *g* and rod *h* with an eccentric *i* on the main shaft *e* in the well-known way of such 80 machines.

The spreader consists of the notched end *j* of a short lateral arm *k* of a lever *l*, located on the side of the needle to which the hook shifts after taking the needle-thread loop *x* 85 and reaching backward a suitable distance toward the main shaft, where it is pivoted at *m* so as to swing horizontally close under the work-plate *n*, said lever having at its pivot end another lateral arm *o*, extending in the 90 opposite direction to that of the arm *k* and connected by a downwardly-extended part *p* of said arm *o*, and the rod *q* with an eccentric *s* on the main shaft, by which the spreader is operated, so as to be thrust forward to engage the hook-thread loop *t* when or about 95 the time the hook begins to retire, to make wide opening for the needle and hold it until the needle has descended so far as to insure the engagement of the hook-thread loop by 100 the needle, as shown in Fig. 6. Then the spreader retires, leaving the loop to be taken up and moving on to the beginning of its next cycle.

I am aware that a pendent stud on the under side of the work-plate has been applied in various ways, so that the hook-thread will be drawn behind it and be caught thereby 5 when the point of the hook is outreaching so far that the thread will draw higher than the point and be for a time held to keep the loop open while the hook retires; but such spreaders are not reliable, as the loops will escape 10 more or less earlier or later for various reasons, and it is exceedingly difficult to adjust the length of the stud so as to cast off the loop at the right time under all circumstances.

It will be seen that in my improved spreader 15 there can be positive holding of the loop as long as desired and as positive release. It will be seen that with this provision for simultaneously opening the hook-loops both ways the effect of so drawing the hook-thread out 20 of line in making such quick turns of the work as is necessary to short turns of the work in rapidly-running machines there will be much less liability of skipping.

What I claim as my invention is—

The combination with the needle and the 25 looping-hook, said hook having the lateral needle - avoiding movement, by which it spreads the hook-thread loops in one direction, and means for operating said needle and hook, of the reciprocating hook-thread-loop 30 spreader simultaneously spreading said loop in the opposite direction, said spreader consisting of a pivoted lever *l* having a lateral arm *k* provided with the notched end, and mounted on the pivot *m* pendent from the 35 work-plate, so as to swing close under the work-plate, said lever having the lateral and pendent arm *o*, *p*, connected with an eccentric *s* on the main shaft.

Signed at New York city this 25th day of 40 February, 1901.

HERMANN A. KLEMM.
